UNITED STATES PATENT OFFICE.

LE ROY W. FAIRCHILD, OF NEW YORK, N. Y.

DESIGN FOR PENCIL-CASES.

Specification forming part of Design No. 11,422, dated September 16, 1879; application filed August 16, 1879.
[Term of patent 7 years.]

To all whom it may concern:

Be it known that I, LE ROY W. FAIRCHILD, of the city, county, and State of New York, have produced a new and original Design for an Ornamental Pencil-Case or other small implement case, of which the following is a full, clear, and exact description, reference being had to the accompanying photographic illustration, making part of this specification.

My invention consists in forming upon a pencil or other small implement case a diminutive jockey-cap and horseshoe.

A is a representation of the design as a whole. b is a ring. It is held loosely in an eye, c. d is a jockey-cap affixed to the closed end of the case immediately below the ring and eye. e is a diminutive horseshoe formed upon the shell of the case about midway between the cap d and the lower end bead, f. The various parts may be shown in different colors, if desired.

What I claim as my invention is—

A design for a pencil or other small implement case, consisting of a diminutive horseshoe, e, upon the side of the case midway its length, jockey-cap d, ring b, eye c, and bead f, substantially as shown and described.

LE ROY W. FAIRCHILD.
